UNITED STATES PATENT OFFICE.

CHARLES M. GREY, OF EAST ORANGE, NEW JERSEY.

ART OF DIE-CASTING.

1,333,754.

Specification of Letters Patent. Patented Mar. 16, 1920.

Application filed March 6, 1919. Serial No. 280,935.

To all whom it may concern:

Be it known that I, CHARLES M. GREY, a citizen of the United States, residing in East Orange, State of New Jersey, county 5 of Essex, have invented certain new and useful Improvements in the Art of Die-Casting, of which the following is a specification.

This invention relates to improvements in 10 the art of die casting and is directed, more particularly, to a method of, and apparatus for, charging the pressure pot of a die casting machine.

In die casting machines, as heretofore constructed, there has generally been employed two pots or receptacles, one containing the bath or pool of the metal, commonly called the "melting pot", and the other termed the "pressure pot" or chamber, from which the 20 metal is forced into the die by either pistons or fluid pressure. This pressure pot or chamber has generally been immersed in the bath or pool of the melting pot, to a greater or less extent, and means have been 25 provided for filling this pressure pot from the metal in the melting pot. These means have consisted of either submerged ports, or means for tilting the nose of the pressure pot beneath the surface of the bath or pool. 30 While submerged ports opened by pistons, working inside the pressure pot have been fairly satisfactory for low melting point metals it has been found that for metals of higher melting points that such pressure 35 chambers are not practical, as the pistons cut and stick at such high temperatures. It has therefore been found more satisfactory to use a pressure pot so mounted in the bath as to allow the nozzle end to be submerged 40 in the bath between shots. While these pots have been found satisfactory, to a greater or less extent, they have certain disadvantages among which are, the necessity of so supporting them that a large portion 45 of the pot is out of the bath when in position for ejecting the metal, the inability to get a full charge in the pressure pot, the tendency to get the dross floating on top of the bath into the pressure pot, and eject 50 same into castings to be produced, the increased tendency of drossing or oxidizing the bath, due to the fact that as the nozzle end of the pressure pot is submerged it causes a quantity of air to be mixed with 55 the bath as the surface of the bath closes in over the submerging end of the pot.

With the foregoing considerations in mind, the object of the present invention is to overcome or minimize the disadvantages adverted to as well as others. 60

Features of the invention, other than those specified, as well as the advantages resulting from the employment thereof, will be apparent from the following detailed description when read in conjunction with 65 the accompanying drawings.

In the accompanying drawings I have illustrated diagrammatically one form of apparatus in which the method of this invention may be practically carried out, but it 70 will be understood, however, that the method may be practised with other forms of apparatus and that the apparatus shown is susceptible to various modifications without departing from the spirit of the invention. 75

Figure 1 is a perspective elevation showing those portions of the die casting machine with which the present invention particularly deals. In this figure the parts are 80 shown in pouring or ejecting position, *i. e.*, the pot is in co-operative relation with the die in which the part to be produced is cast.

Fig. 2 is a view similar to Fig. 1, but showing the parts in the relative positions 85 which they occupy during the operation of charging the pressure pot.

Referring to the drawings, A indicates a melting pot containing a pool or bath of molten metal B, which forms the source of 90 supply for the pressure pot. It is the usual practice to mount the melting pot A in a suitable furnace of which it forms a part and to heat said pot externally by any suitable source of heat. 95

The pressure pot C may, of course, partake of different shapes, but is here shown as substantially U-shaped. The interior of the pot is hollow, and is provided at one end, with a nozzle D adapted to co-operate with 100 a die E in such manner as to feed molten metal from the pot to the die, while the other end of the pot is connected in any suitable manner, preferably by a flexible tubing F, to a suitable source of fluid pressure, whereby the metal in the pressure pot may be forced through the nozzle D into the die. The pot is preferably supported for movement in a horizontal plane on a hanger G by means of a pivotable connection g and 110 the link connection g'. The link connection g' is made adjustable for the purpose of

obtaining accurate alinement between the nozzle D and the inlet to the die, and the hanger G is mounted for sliding movement longitudinally of a pair of guides H suitably mounted in fixed position in the machine. By mounting the pot as described, it may be slid toward and away from the die so as to occupy the operative or shooting position of Fig. 1, or the filling position of Fig. 2. Any suitable means may be provided for so shifting the pot. By suspending the pot in the manner described, a portion of the pot is immersed in the molten metal B, and serves to maintain any metal which may be contained in the pot in the desired molten condition.

Associated with the machine is a vacuum bell I, suspended by a link J, and adapted to be raised and lowered by any suitable means such as a pivoted lever K fulcrumed at k and controlled by any suitable mechanism. The bell I is so positioned in the machine that, when elevated, it is suspended above the position occupied by the nozzle end of the pot when said pot is retracted from the die and in the filling position shown in Fig. 2. The bell is, however, of such shape and proportions that it may be lowered from the elevated position shown in Fig. 1 to the depressed position of Fig. 2, wherein the lower mouth of the bell will occupy a position below the surface of the pool of metal B and the nozzle end of the pot will be housed within the confines of the bell. The interior of the bell communicates, preferably through a flexible communication L, with a suitable vacuum system for exhausting the air from the bell when said bell is in the position of Fig. 2, with the result that the exhaustion of the air from the bell at this time will cause the molten metal B to be drawn up into the bell so that the surface of said metal rises in the bell appreciably above the opening of the nozzle D, as clearly shown in Fig. 2. It will thus appear, that, since the metal level in the bell is above the opening of the nozzle D and that as the back end of the pressure pot is open to the atmosphere through the compressed air inlet F, which is connected to a suitable valve system, the metal will flow through nozzle D and into the pot, thereby charging the same.

In case there is not sufficient metal in the pressure pot to fill the upwardly projecting nozzle end of the pot and still more than fill the connecting portion between the two ends of the pressure pot, then either the outlet at the back end of the pot must be closed or other means used for obtaining a primary charge in the pressure pot.

In practice, the exhausting of air from the bell and pot is accomplished very speedily, with the result that the metal level in the bell rises quickly to the position shown

in Fig. 2, wherein its level is above the nozzle D, and, accordingly, the metal which flows into the pot is drawn from the metal in the bell at a point therein below the surface of said metal. As a result, the metal with which the pot is charged is free from dross or other impurities which normally float on the surface thereof.

The degree to which the pot may be filled may be readily governed by the period which is allowed to elapse between the exhaustion of air in the bell and the breaking of the vacuum so that in this manner the pot may be either entirely filled or may be only partially filled as the operator desires.

The operation of the device may be briefly outlined as follows. The pressure pot having been moved to the filling position and the partial vacuum built up in the bell I, while positioned over the nozzle end of the pot, the metal rises in the bell and flows into the pot in the manner shown in Fig. 2. When the pot is charged as desired, the vacuum is broken in the bell, allowing the metal therein to fall back to the liquid level of the pot A and the bell is then raised out of the path of the pot. The pot is next moved forwardly by suitable mechanism to the position shown in Fig. 1 wherein the nozzle D is brought into cooperative relation with the sprue of the die E. This having been accomplished, fluid pressure is admitted through the connection F and forces the metal in the pot through the nozzle D and into the die in the manner well known to the art. After the die has been filled, the pressure in connection F is shut off and the pot moved back to the position of Fig. 2, whereupon the bell I is again lowered over the nozzle end of the pot and the recharging and casting operations repeated.

An important practical advantage in the charging of the pot in the manner specified is that the molten metal drawn up into the bell entirely surrounds the nozzle D and thereby serves to melt off any metal which may have partially solidified at the mouth of the nozzle from the previous casting operation. As a matter of fact, the nozzle is maintained at such temperature that obstruction thereof through the solidifying of small quantities of metal therein is entirely obviated. In carrying out the method described, the pot is shown as movable toward and away from the die and an apparatus for carrying out the method in this manner is shown in the drawing.

In the charging of a pot in the manner described, the metal which flows into the pot is not only free from slag and dross but is also free from entrained air, since, when the bell is down over the pot, the operation of exhausting the bell, of course, exhausts all the air from the pot simultaneously so that the pot contains a partial vacuum before the

metal rises in the bell. As a result of this feature of the method, the metal which is subsequently forced from the pot into the die is more free from entrained gas than in the ordinary practice, thereby producing better castings.

Having thus fully described my invention, what I claim as new and desire to secure by Letters Patent is:

- 10 1. In the art of die casting, the method of charging the pressure pot which consists in pneumatically raising the level of a portion of the bath in which the pressure pot is supported above the normal level of the bath and by such change of level causing the metal to flow into the pressure pot.
- 15 2. In the art of die casting, the method of charging the pressure pot which consists in feeding the molten metal thereto from the melting pot and from beneath the surface of the metal in said melting pot by pneumatic means, whereby the pressure pot is charged without introducing dross therein.
- 20 3. In the art of die casting, the method of charging the pressure pot which consists in pneumatically raising the liquid level of the metal of the melting pot in the vicinity of the charging opening of the pressure pot to such height that the metal is fed through said opening into the pressure pot.

- 25 4. In the art of die casting, the method which consists in so positioning a pressure pot within the melting pot that the metal feed inlet to the pressure pot is located above the normal level of the bath in the melting pot, thereafter incasing said inlet in a receptacle the lower end of which is sealed by the metal of the bath, then exhausting air from said receptacle and the inlet end of the pressure pot whereby the metal is drawn into the receptacle and above the inlet to the pressure pot and feeds into said inlet to charge the pot.

- 30 5. In the art of die casting, the method which consist in producing a vacuum around and in the charging end of a pressure pot and above the normal level of the metal in the melting pot, whereby said vacuum raises a portion of the metal above its normal level and above the charging end of the pressure pot and feeds the metal into said pot.

- 35 6. In the art of die casting, the method of charging the pressure pot which consists in pneumatically causing molten metal to flow into the pot at a point above the normal level of the bath of metal in the melting pot and while said pot is retracted from operative relation to the die, moving the pot into coöperative relation with the die and then forcing the metal from the pot into the die by pneumatic pressure.

- 40 7. In a die casting machine, a pressure pot, having its metal charging end positioned above the level of the metal in the

main bath from which said pot is to be charged, in combination with pneumatically operated means for raising a portion of the metal of the bath to a point above the charging inlet to the pot whereby metal is fed to the pot.

70 8. In a die casting machine, a pressure pot, having its metal charging end positioned above the level of the metal of the main bath from which said pot is to be charged, a receptacle adapted to inclose the charging end of the pressure pot with its lower end sealed by the metal of said bath, in combination with means for exhausting the air from said receptacle and the charging end of the pot whereby the metal rises 75 in the receptacle and is fed therefrom to the pressure pot.

80 9. In a die casting machine, the pressure pot adapted to be partially submerged in the bath of the melting pot, a vacuum bell adapted to be lowered over the charging end of the pressure pot and to have its lower end sealed by the metal in the bath, and means for exhausting the air from the bell and charging end of the pressure pot whereby 85 the molten metal rises in the bell above the charging inlet to the pressure pot and feeds into the latter.

90 10. A die casting machine, embodying a die, a pot mounted for movement toward and away from the die, which pot is adapted to be partially submerged in a molten metal pool, a vacuum bell normally occupying a position out of the path of the pot but adapted to be lowered over the pot with its lower 95 end sealed by the metal in the pool when the latter is in a position retracted from the die and means for exhausting the air from the bell and feeding end of the pot for the purpose of causing the metal to rise therein 100 to a sufficient height to charge the pressure pot.

105 11. A die casting machine embodying a pot adapted to be partially submerged in a molten metal pool, and a die, one of which 110 is movable toward and away from the other so that they are brought into and out of co-operative relation and vacuum means co-operating with the pot, when the parts are out of coöperative relation, for elevating a 115 portion of metal in the pool and causing it to flow into the pot.

120 12. A die casting machine, a melting pot, a pressure pot positioned therein, a die, means for causing a relative to and fro movement between the pressure pot and the die, in combination with vacuum means for charging the pressure pot with molten metal at a point above the normal level of the metal in the melting pot.

125 In testimony whereof I have signed my name to this specification.

CHARLES M. GREY.
